UNITED STATES PATENT OFFICE.

GEORGE GRAFF, OF TOLEDO, OHIO, ASSIGNOR TO THE DURA COMPANY, OF TOLEDO, OHIO, A CORPORATION OF DELAWARE.

DESIGN FOR A HANDLE FOR DOOR LATCHES OR THE LIKE.

Application filed March 7, 1927. Serial No. 21,000. Term of patent 14 years.

To all whom it may concern:

Be it known that I, GEORGE GRAFF, a citizen of the United States of America, residing at Toledo, in the county of Lucas and State of Ohio, have invented certain new, original, and ornamental Design for a Handle for Door Latches or the like, of which the following is a specification, reference being had therein to the accompanying drawings, forming a part thereof, in which—

I claim:

The ornamental design for a handle for door latches or the like, substantially as shown.

GEORGE GRAFF.
